ENGLEWOOD, NEW JERSEY

ONE-PIECE PLUG AND RECEPTACLE

Application filed May 29, 1931. Serial No. 541,044.

This invention relates to electric fixtures and one object of the invention is to provide a fixture which may be used for ornamental or advertising purposes and so constructed that bulbs carried by companion sections of the fixture may be disposed in such relation to each other that they will form words, symbols or an ornamental border or background for a sign.

Another object of the invention is to so construct the companion sections or units that they may be easily connected, one to another, and any number desired used and disposed either in alinement or at any desired angle relative to each other.

Another object of the invention is to provide units each carrying a bulb receiving socket at one end and having at its other end a terminal adapted to pivotally connect the unit with the socket carrying end of another unit and establish an electrical connection between the same whereby current may pass from one to the other.

Another object of the invention is to permit companion units to be easily attached to each other and while preventing them from accidentally separating, allow them to be easily detached from each other when desired.

Another object of the invention is to provide units of this character wherein each has embedded therein conductors which are hidden from view and serve very effectively to transmit electric current from one unit to another and cause bulbs engaged in sockets of the units to be illuminated.

Still another object of the invention resides in providing a device which is simple and durable in construction, inexpensive to manufacture and one which will be very efficient in operation.

With these and numerous other objects in view, my invention consists in the novel features of construction, combination, and arrangement of parts as will be hereinafter referred to and more particularly pointed out in the specification and claims.

In the accompanying drawings forming a part of this application:

Figure 1 is a view in elevation showing

a number of units connected to each other and carrying bulbs;

Figure 2 is a top plan view of the units shown in Figure 1;

Figure 3 is a sectional view showing a pair 55 of units separated;

Figure 4 is a similar view showing the units united;

Figure 5 is a side elevation of one unit 60 and a feeder plug;

Figure 6 is a bottom plan view of the unit shown in Figure 5;

Figure 7 is a view similar to Figure 4 showing a shield engaged in the socket of the unit instead of a bulb.

In describing the invention, we shall refer to the drawings in which similar reference characters designate corresponding parts throughout the several views. This improved electrical fixture consists of a plurality of 70 sections or units 1 which are of a duplicate construction and any number found necessary may be used. They may extend in alinement or transversely of each other and may be disposed at any angle desired in order to 75 form letters, symbols or a suitable background or border.

Each unit is formed of insulating material and consists of a shank 2 having a socket 3 at one end and a plug 4 at its other end for engagement in the pocket 5 of the socket of an adjoining unit in order to releasably connect the units and permit them to be swung transversely of each other to adjusted positions. A latch 6 which is slidably mounted 85 for movement into and out of an operative position retains adjoining units in engagement with each other and since it is mounted against the rear face of the shank, it will be hidden from view and prevented from detracting from the appearance of a sign.

Referring to Figure 3, it will be seen that the socket 3 has a shell 7 mounted therein to receive the base 8 of a bulb 9. The center terminal 10 which is insulated from the shell extends into the pocket 5 and carries jaws 11 to engage about the metal head 12 of the plug 4. A bolt 13 connects the shell 7 with a terminal plate 14 and this plate is formed with an opening to receive the plug and car- 100

ries depending jaws 15 to firmly grip a metal band 16 which fits tightly about the reduced portion of the plug. By this arrangement, the jaws will have firm, gripping engagement 5 with the head 12 and band 16 and current may pass through the wires 17 and 18 from one unit to another. The wires are embedded in the unit longitudinally thereof, the wire 17 having one end attached to the stem of the 10 terminal 10 and its other end joined to the band 16 and the wire 18 having one end attached to the plate 14 and its other end joined to the head 12. A ring 19 which is formed of insulating material is screwed into 15 the open end of the pocket 5 and is of the proper diameter to fit snugly about the plug 4 and prevent the plug from having transverse movement which would be liable to bend the jaws 11 and 15 out of shape. Disks 20 20 formed of metal and serving as reflectors or decorative backgrounds for the bulbs are fitted upon the front ends of the sockets 3 where they are secured by rings 21.

In order to form a sign or other electrical 25 display, the units are connected by fitting the plug at one end of a unit into the pocket 5 of another and the latch 6 of the second unit is moved to an operative position in which it extends beneath the plug carrying end of the 30 first unit and holds the plug in the pocket with its head 12 and band 16 gripped by the jaws 11 and 15.

By using a suitable number of units and 35 disposing in proper angular relation to each other a name or ornamental design can be formed. Current is supplied by feed wires which have their ends embedded in a terminal plug 23 carrying a neck 24 corresponding 40 to the plug 4 and having mounted thereon a metal head 25 and band 26 to which the wires 22 are attached. This plug has its neck or stem 24 engaged in the pocket 5 of the end unit and at their other ends the wires 22 may be attached to a plug for engagement 45 in a wall socket. When it is desired to omit one or more bulbs when forming words or portions of a design the sockets 3 from which bulbs are omitted should be shielded in order to prevent water from entering 50 the sockets and forming a short circuit if the sign is mounted out of doors. Therefore, each socket from which a bulb is omitted will be closed by a cap or filler 27 having a threaded neck 28 which is screwed 55 into the shell 7 and a gasket 29 is fitted about the neck in order to bear against the end of the socket and form a water tight joint.

From the foregoing description of the 60 construction of our improved electric fixture, the operation thereof and the method of applying the same to use will be readily understood. It will be seen that we have provided a simple, inexpensive and efficient means for carrying out the objects of the 65 invention and while we have particularly

described the elements best adapted to perform the functions set forth, it is obvious that various changes in form, proportion and in the minor details of construction may be resorted to without departing from the spirit 70 or sacrificing any of the principles of the invention.

Having thus described the invention what is claimed is:

1. In an electric fixture, a plurality of 75 units each having a bulb receiving socket at one end and a pocket beneath the socket, a plug being provided at the other end of each unit, to engage in the pocket of an adjoining unit, a shell in said socket to receive the base of a bulb, a center pin extending from said socket into said pocket, an eccentrically located shell pin extending from said shell into said pocket, a head of conductive material carried by said plug, a collar of conductive material carried by said plug, conductors extending longitudinally in said unit and at one end thereof extending into the plug and connected to the head and collar, a plate in said pocket engaged by the shell 80 pin and one conductor and having jaws to engage the collar of a plug, and jaws carried by the center pin to engage the head of a plug.

2. In an electrical fixture, a plurality of 85 duplicate units, each consisting of a bulb receiving socket and an arm formed integral therewith and projecting transversely from the socket, a plug projecting upwardly from the free end of said arm, conductors extending longitudinally through said arm and into said socket, terminals carried by said plug and engaged by said conductors, and terminals in said socket engaged by the other ends of said conductors and constituting means 90 to grip the plug and terminals thereof of a companion unit and releasably connect the units for pivotal movement relative to each other and establish electrical communication 95 between their conductors.

3. In an electric fixture, a plurality of 100 duplicate units each consisting of a bar having a socket extending upwardly from one end and a plug rising from its other end, a pocket being formed in the lower portion of said socket and opening through its lower end to receive the plug of an adjoining unit, and the lower portion of the socket being recessed to receive the free end portion of 105 an arm of an adjoining unit when the plug thereof is inserted into the pocket and disposed under faces of the units flush with each other, contacts carried by said plug, clutches in said pocket to grip the plug and engage the contacts thereof, a bulb receiving 110 shell and center contact in said socket connected with said clutches, and conductors extending longitudinally through said bar and into said socket with their ends connected 115 with the clutches and contacts of the plug.

4. In an electric fixture, a plurality of duplicate units each consisting of a bar having a socket extending upwardly from one end and a plug rising from its other end, a pocket being formed in the lower portion of said socket and opening through its lower end to receive the plug of an adjoining unit, a bulb receiving shell and center contact in said socket, contacts carried by said plug, conductors extending longitudinally through said bar and connected with the contacts of the plug and shell and center contact of the socket, and means in said pocket to grip the plug to pivotally connect adjoining units and establish communication between the conductors of the units.

5. In an electric fixture, a plurality of duplicate units each consisting of a lamp receiving socket and a rigid arm projecting transversely thereof and formed with a plug at its free end, the plug and socket having spaced contacts insulated from each other, and conductors extending through said arm and connecting contacts of the socket with contacts of the plug, the plug being releasably engageable with the socket of an adjoining unit and when in place serving to pivotally connect the units for swinging movement transversely of each other and establish communication between conductors of the connected units.

6. In an electric fixture, a plurality of units each having a bulb receiving socket rising from one end and a plug rising from its other end to engage in a pocket opening through the bottom of the socket of an adjoining unit and releasably connect the units in overlapped relation for swinging movement transversely of each other to adjusted positions, and conductors embedded in each unit and extending longitudinally through the same from the socket to the plug thereof whereby current may pass through the units from one to another and illuminate bulbs engaged in the sockets.

In testimony whereof, we affix our signatures.

JOHN H. PERONI.
SIDNEY H. ALEXANDER.
